UNITED STATES PATENT OFFICE.

HARRY C. BRATT, OF DAYTON, OHIO.

GOLF TEE OR THE LIKE.

Application filed June 29, 1927. Serial No. 202,207.

This invention relates to improvements in golf tees.

In the accompanying drawings which serve for illustrating the invention:

5 Fig. 1 is a view in elevation of the improved tee in one form;

Fig. 2 is a vertical sectional view of the tee;

10 Fig. 3 is a view in elevation of the tee in modified form;

Fig. 4 is a vertical sectional view of Fig. 3;

Figs. 5-6 are diagrammatic views illustrating the curvatures upon which the tees in the respective forms are developed.

15 The peg type of golf tee has become popular because of its simplicity and convenience, being always ready for use and adaptable under all conditions of the ground for poising the ball for the strike-off. Many forms 20 of these simple devices are disclosed in the art but few have been developed with consideration given to highly important features of golf tees as understood by those skilled in the game.

25 The patent to Patterson No. 1,609,040, issued November 30, 1926, is here cited as setting forth an example of golf tee of the peg type which may be said to be developed along an exact understanding of the conditions of 30 use, and with appreciation of salient features of tees rightly made for discriminating players who take into consideration every factor that may influence the skill of the player and the result of the game.

35 The ease and depth of penetration of the tees of the ground, their firmness as seated in the ground, and accuracy for poising the ball, are features of first importance; durability for repeated use, and form which determines 40 the cost of production and price to the user are also important factors which require consideration.

To this end the improved tee as illustrated in Figs. 1-2 is formed integrally of any suitable material, preferably wood, and consists of a head or body portion 1 extended above the ground as the tee is set, the head being generally round or oval shaped and provided with a concave recess 2 for seating the ball 50 which is outlined at 3. The stem or peg portion 4 of the tee is formed on a downwardly extended concavical curve being an extension of the curve upon which the lower portion of the head is formed and substantially on the 55 radius of a circle between lines $b-d$ as illustrated in Fig. 3. The extension 5 of the peg

below line $-d$ is substantially straight, the end 6 being pointed for penetrating the ground.

The round or oval formation of the head 60 serves for giving ample body proportions to the tee and greater strength for withstanding the blow as the ball is struck off, the gradual taper of the head in opposite directions from its horizontal medial line $-a$ is effective 65 for minimizing the tendency of the head to chip or split which is a fault of wood tees which have a more or less sharply defined, or outwardly under-cut rim at the ball seat. The relatively greater strength of the improved tee in this respect is illustrated in 70 the vertical sectional view of the head in Fig. 2, the rim 7 of the seat being cone-shaped in cross section with the apex of the rim well within the plane of the body of the tee, thus 75 effecting fullness of the body and longer grain of the wood which tends to minimize chipping and splitting of the heads.

The improved shape of the head of the tee is also of material advantage in production, 80 as it permits of making the usual allowance for variations in dimensions in wood turning without materially affecting the approved form of the tees. In wood tees having an undercut or sharply defined, horizontally ex- 85 tended ball seat rim, ordinary variations in wood turning result in production of a large percentage of tees which are under size in the dimensions of the head and unevenly formed as to the ball seat, being thus of inferior 90 quality and accordingly unsatisfactory to the user.

Upon seating the tee illustrated in Figs. 1-2, and to better effect in Fig. 5 as to its lines of construction, in the ground the end 95 of the peg will penetrate the ground easily to an undefined depth illustrated by line $-c$, the sharp outward rise in the curve of the head of the tee then acting to exert pronounced resistance to further penetration, 100 and at the same time by the wedging action of the enlarged portion to press the ground around the peg and to prevent rising movement of the tee by "sponging" action of the ground when the pressure for seating the tee 105 in the ground is removed.

The tee firmly set in the ground also has greater strength for withstanding the force of the blow as the ball is struck off, this being due to the relatively short, thick neck of the 110 tee at the ground line, the possibility of breaking at this point being thus minimized.

The modification of the improved tee illustrated in Figs. 3-4 and 6 consists in the shape of the head of the tee which is convexo-convex as distinguished from the round or oval shaped head described in connection with Figs. 1-2 and 5. The opposite convex surfaces 8-9 of the head incline inwardly from a medial cylindrical portion 10 of substantial width, the upper inclination resulting in cross sectional cone formation of the ball seat rim 11, as indicated at 12 in Fig. 6, being substantially the same as the seat formation 7 illustrated in Fig. 5 and serving in like manner to minimize the tendency of the head of the tee 15 to chip and split.

The formation of the under side of the head of the tee and the extension of the stem therefrom is substantially on the radius of a circle as illustrated by the curve —h in Fig. 6, the 20 formation between lines f—g being thus convexo-concavical. The extension 13 of the stem below line —g is substantially straight, the end 14 being pointed similar to the formation shown in Fig. 1.

The curve —h of the modified formation of 25 the tee being substantially longer than the corresponding curve —e of the development illustrated in Fig. 5, a longer taper is given to the stem which results in easier penetration of the ground as the tee is set for the strike-off. 30

From the foregoing detailed description, the novel formation of both forms of the improved tee and the advantages derived therefrom will be apparent to those experienced in playing golf. 35

Having described my invention, I claim:

A golf tee formed integrally of wood including a head having an annular medial portion, opposite annular faces inclined upward and downward respectively and inward from 40 said portion, a concavical seat formed in the upper face for poising a golf ball, and a stem for setting the tee in the ground extended from the lower face, the stem flaring upwardly and outwardly in a concavical curve and 45 merging into the head.

In testimony whereof, I affix my signature.
HARRY C. BRATT.
